S. S. COLT.
METHOD OF PRODUCING BUILDING UNITS.
APPLICATION FILED OCT. 26, 1917.

1,262,308.

Patented Apr. 9, 1918.

UNITED STATES PATENT OFFICE.

SAMUEL S. COLT, OF ORANGE, NEW JERSEY.

METHOD OF PRODUCING BUILDING UNITS.

1,262,308.

Specification of Letters Patent. Patented Apr. 9, 1918.

Application filed October 26, 1917. Serial No. 198,725.

To all whom it may concern:

Be it known that I, SAMUEL S. COLT, a citizen of the United States, residing at Orange, in the county of Essex, and State 5 of New Jersey, have invented certain new and useful Improvements in Methods of Producing Building Units; and I do hereby declare the following to be a full, clear, and exact description of the invention, such as will 10 enable others skilled in the art to which it appertains to make and use the same, reference being had to the accompanying drawings, and to characters of reference marked thereon, which form a part of this specification. 15

This invention has reference, generally, to a novel body having a "dash" or "thrown-on" finish, said body being in the form of a unit, block or wall of concrete, or any other 20 body, such as wood, brick or stone, the invention relating more particularly to a novel method of producing and finishing such body.

The present invention therefore has for 25 its principal object to provide a novel method or process of body having a "dash" or "thrown-on" finish, said body being in the form of a unit, block or wall of concrete, or any other body, as wood, brick or 30 stone, with a view of providing a most artistic effect, and providing when applied in the form of a finished structure, an ornate structure having the appearance upon its face of being a construction laid up in finished stone.

Other objects of the present invention not at this time more particularly enumerated will be clearly understood from the following detailed description of the present invention.

With the various objects of the present invention in view, the invention consists in the production of a novel process or method of producing a body having a "dash" or 45 "thrown-on" finish, a portion of the surface being ground away or otherwise removed, said body being in the form of a unit, block, or wall of concrete, or any other body, such as wood, brick, or stone.

50 In carrying out the method or process, the unit, body, or wall to which the "dash"

or "thrown-on" finish is to be applied can be molded by any system of molding for concrete or the like, or may be any rough surface such as metal lath or wire mesh applied to wood structures, or may be made of brick or rough stone, the "dash" or "thrown-on" material being generally a mixture of sand and cement, but may be of other known materials, which, after it is properly prepared, is thrown onto the surface to any desired degree of thickness by the aid of a whisk broom or other suitable means, and when dry has the appearance of a stippled surface, but more beautiful; any desired portion or portions of the "dash"-coat, when sufficiently dry, then being ground away, or otherwise removed, to form upon the "dashed-on" or stippled surface of the unit, block or body, various designs, all of which 70 will be well defined and cause the parts of the "dash"-coat to stand out in bold relief with clearly defined forms or shapes, free from the defects usually found present when made by other methods.

In the accompanying drawings, I have illustrated both a unit, in the form of a block, and a wall, representing the finished product, as well as the various steps in carrying out the novel method or process 80 of the invention.

Referring now more particularly to the several figures of the drawings, Figure 1 is a perspective view of a single unit or block molded from concrete or representing a 85 rough stone, or a brick; Fig. 2 is a similar view of the same, but having its entire main face or surface provided with a "dash" or "thrown-on" finish or veneering of sand and cement, or the like, and Fig. 3 is a transverse 90 vertical section of the unit or block represented in said Fig. 2.

Fig. 4 is a face view of the finished unit or block, showing the "dash"-coat face of the unit or block with portions of the "dash" or "thrown-on" finish ground or cut away; and Fig. 5 is a transverse vertical section of the 95 said unit or block.

Fig. 6 is a face view of a finished wall made according to and embodying the 100 principles of the present invention; and Fig. 7 is a horizontal sectional representation of

the same, said section being taken on line 7—7 in said Fig. 6.

Similar characters of reference are employed in the said above described views, to indicate corresponding parts.

In carrying out my present invention, I will first refer to Figs. 1 to 5 inclusive, in said figures, the reference-character 1 indicating a unit in the form of a block of concrete which is molded in the usual form or mold in the usual manner. In lieu of a concrete block, it will be evident, however, that this unit 1 may be a rough stone, or a brick, or other suitable base or body.

15 The "dash" or "thrown-on" finish is indicated by the reference-character 2, and the same consists, generally, of a suitable mixture of sand and cement, or a suitable mixture of other materials, which is properly prepared so as to be of proper plastic consistency, and is then applied to the face or surface 3 of the unit or block 1, by being dashed or thrown onto said surface by the aid of a whisk broom or other suitable means.

20 This "thrown-on" finish is thereupon allowed to dry sufficiently so as to have the appearance of what is known in the trade as a "dash"-coat or "stipple"-face. After this "dash" or "thrown-on" finish is sufficiently dry a portion of such surface is removed or ground away, as at 4, see Figs. 4 and 5 of the drawings, the removal of the surface-portion or portions being accomplished by grinding or rubbing away the 25 "thrown-on" finish to any desired depth by means of carborundum, stone, or any other means, which will produce a smooth and flat finished surface.

30 As shown in the accompanying drawings, in Figs. 4 and 5, the unit or block is provided with a smooth and flat margin, which illustrates one embodiment of the principles of the present invention. It will be evident, however, that other portions of the "dashed" or "thrown-on" surface or veneer of the unit or block may be ground away or rubbed off, whereby the face of the unit or block is provided with smooth and flat finishes of innumerable designs.

35 50 In lieu of applying the present invention to the production of a single unit in the form of a concrete block, stone, or brick, as heretofore described, the invention can be applied in the production of a concrete wall, bridge-structure, or the like, over a 55 large surface, as will be evident from an inspection of Figs. 6 and 7 of the drawings.

As indicated in said figures, the reference-character 5 designates a large concrete or 60 other suitable body, made in a form, and 6 designates a "dash" or "thrown-on" finish, which is applied in the manner herein-above stated, over the entire surface or face of

the said body. When the said finish or veneer is sufficiently dry, desirable portions 65 thereof, as 7 and 8, are ground away, or rubbed off, or otherwise removed, to provide the smooth and flat surface-portions illustrated in said figures, and whereby a wall in imitation of laid-up stone is produced.

To more fully enhance the artistic effect, if desired, channels or grooves, as 9 and 10, may also be produced in the smooth and flat surface-portions to represent joints.

75 From the foregoing description of my present invention it will be clearly seen that I have produced a novel and simple means and method of providing a building unit in the form of a block, body, wall, or other 80 structure, the face of which is provided with a "dash" or "thrown-on" finish or veneer, having a portion or portions thereof ground away, or rubbed down, or otherwise removed to a desired depth, so as to provide 85 a flat and smooth margin or other ornamental effect, and which will cause the "dash"-coat to stand out in bold relief; and, furthermore, by my novel method of producing the same providing clearly defined forms 90 and shapes of increased ornamental design and effect, free from defects and such as are not at present by the methods in ordinary use.

95 I claim:—

1. The method herein described in producing a building unit comprising a body in the form of a block, wall, or the like, which consists in applying to the face of said body a "dash" or "thrown-on" finish, 100 and then grinding away a portion of said finish.

2. The method herein described in producing a building unit comprising a body in the form of a block, wall, or the like, 105 which consists in applying to the face of said body a "dash" or "thrown-on" finish, and then grinding away those portions of said finish lying adjacent to the marginal edge-portions of said body to provide a flat 110 and smooth margin.

3. The method herein-described in producing a building unit, by molding a body in the form of a block, wall, or the like, of concrete, stippling the surface of said body 115 and grinding away a portion of the stippled surface to produce a bold relief of said stippled surface.

4. The method herein-described in producing a building unit, by molding a body 120 in the form of a block, wall, or the like, of concrete, stippling the surface of said body, and grinding away the marginal portions of the stippled surface to produce a bold relief of said stippled surface.

125 5. The method herein-described in pro-

ducing a building unit, by molding a body of concrete in the form of a block, wall, or the like, dashing or throwing onto a surface of said body a veneer of concrete, and grinding away a portion of said veneer.

6. The method herein-described in producing a building unit, by molding a body of concrete in the form of a block, wall, or the like, dashing or throwing onto a surface of said body a veneer of concrete, and grind-

ing away the marginal edge-portions of said veneer.

In testimony, that I claim the invention set forth above I have hereunto set my hand this 23rd day of October, 1917.

SAMUEL S. COLT.
